Attorneys.

UNITED STATES PATENT OFFICE.

WILLIAM H. PENDERY, OF WYOMING, OHIO, ASSIGNOR TO EMMA D. PENDERY, OF SAME PLACE.

BAG-HOLDER.

SPECIFICATION forming part of Letters Patent No. 445,195, dated January 27, 1891.

Application filed August 11, 1890. Serial No. 361,724. (No model.)

To all whom it may concern:

Be it known that I, WILLIAM H. PENDERY, a citizen of the United States, residing at Wyoming, in the county of Hamilton and 5 State of Ohio, have invented certain new and useful Improvements in Bag-Holders, of which the following is a full, clear, and exact description, reference being had to the accompanying drawings, forming part of this specification.

My invention relates to a convenient means of supporting a bag or sack and holding its mouth open while being filled, and has for its object the improved construction of such 15 holders, whereby their simplicity and efficiency are increased.

The novelty of my invention will be herein-after set forth, and specifically pointed out in the claims.

20 In the accompanying drawings, Figure 1 is a perspective view of my improved bag-holder as applied to an ordinary mill-truck. Fig. 2 is a plan view of the holding-jaws and connected parts in open position. Fig. 3 is a 25 side elevation of the holder with the jaws closed. Fig. 4 is a rear elevation of the bracket and supporting-rod. Fig. 5 is a side elevation showing the application of my improved holder to the delivery-spout of a mill. Fig. 30 6 is a sectional view through the dotted line $x x$ of Fig. 1.

The same letters of reference are used to indicate identical parts in all the figures.

I employ two semi-elliptical or semicircular jaws A B, hinged together, as at a , at their outer ends and beveled at their edges, as seen in Fig. 6, so that when shut they readily clamp between them the previously-inserted edge of one side of the bag or sack. These 35 jaws are supported by a central arm C, fast to the jaw B, extending back under the same for a short distance, then up, and finally terminating in a horizontal extension having an aperture for the passage of the supporting- 40 rod D. In addition to passing through the aperture of the arm C, the rod D passes through an eye or perforation in the end of a bolt b , inserted through a perforation in the vertical portion of the arm C. A coiled 45 spring c surrounds the bolt between its head and the arm C and serves to aid the weight

of the jaws A B in tilting the arm C, and thereby causing it to pinch or bind upon the supporting-rod D, while at the same time the jaws may be adjusted up or down by hand 55 upon the rod D to suit the length of the sack to be filled.

The supporting-rod D may be attached in a variety of ways to a variety of objects, as will best suit the requirements of a mill. In 60 Figs. 1, 3, 4, and 6 I have shown a very convenient and novel way of removably attaching it to a mill-truck. Here the upper part of the rod D is bent back and then downward, as shown, to form a rear leg, which is inserted through perforations in a bracket-plate d , secured to the rear or under side of the upper bar of the truck. The lower end of the leg has a circumferential groove, which is engaged by a spring e (see Fig. 4) to prevent the accidental displacement of the supporting-rod. Again, in Fig. 5 I have shown the supporting-rod bolted or screwed to the side of a delivery-spout E. 70

Returning to the construction and operation of the jaws, it will be seen, in referring to Fig. 1, that there is a cut-out portion on each side of the jaw B, as at f . This is to provide clearance for the edge of the bag and to enable the fold to be more readily 80 made. When the jaws are open, a suitable stop is provided to hold them in a horizontal position, the edge of one side of the bag is folded over B, and A is then turned over and clamped by frictional contact upon it. By 85 reason of the fixed jaw B being supported by the arm C at or near its middle, and having the movable jaw A hinged to or at its outer ends, the diametrical space between the opposite ends of the jaws is left entirely free 90 and open, and when the bag is clamped in the holder its loose edge hangs down on the side facing the operator who fills the bag, and no obstruction is presented to the shovel or other filling device which he may use. 95

Secured upon the jaw A at its pivotal point is an arm F, upon the end of which is a box or hollow sphere G for carrying a ball of twine, the end of which emerging from an aperture in the box is cut off against a knife 100 g, secured to the box or its arm, in proper lengths to tie the sack when filled. In addi-

tion to its function as a twine-carrier, the arm F serves as a convenient handle for turning the jaw A, as will be readily understood.

5 Having thus fully described my invention, I claim—

1. In a bag-holder, the fixed clamping-jaw approximately semicircular in form and supported at or near its middle, in combination with the co-operating movable clamping-jaw of similar shape and hinged at the outer ends of the fixed jaw, so as to swing over upon the same, whereby the space between the opposite ends of the jaws is left open, for 15 the purpose described.

2. In a bag-holder, the fixed clamping-jaw approximately semicircular in form, and a vertically-adjustable support for the same secured to it at or near its middle, in combination with the co-operative movable clamping-jaw of similar shape and hinged at the outer ends of the fixed jaw, so as to swing over 20 upon the same, substantially as and for the purpose described.

3. In a bag-holder, the fixed clamping-jaw 25 approximately semicircular in form and supported at or near its middle, in combination with the co-operating movable clamping-jaw of similar shape and hinged at the outer ends of the fixed jaw, and a twine-carrier secured to the hinged jaw and serving as an operating-handle therefor and provided with a twine-severing knife, substantially as described.

4. The combination and arrangement of the 30 hinged jaws A B, arm C, fast to the jaw B and provided with the spring tilting-bolt b, and supporting-rod D, substantially as described.

5. The combination and arrangement of the 35 hinged jaws A B, arm C, fast to the jaw B and provided with the spring tilting-bolt b, supporting-rod D, bracket-plate d, and spring e, substantially as described.

WILLIAM H. PENDERY.
